CLAIM

The ornamental design for a packaging for fraud detection in a portable device, as shown and described.

DESCRIPTION

FIG. 1 is a front perspective view showing our new design for a packaging for fraud detection in a portable device;

FIG. 2 is a rear elevational view of the packaging seen in FIG. 1; and,

FIG. 3 is a right side elevational view of the packaging seen in FIG. 1.

The dotted lines in FIGS. 1-3 indicate the frangible portion of the packaging forming part of the claim.
